UNITED STATES PATENT OFFICE.

HUGH V. JOBE, OF ROLL, OKLAHOMA.

TELEPHONE ATTACHMENT.

1,236,567.

Specification of Letters Patent. Patented Aug. 14, 1917.

Application filed May 31, 1916. Serial No. 100,931.

To all whom it may concern:

Be it known that I, HUGH V. JOBE, a citizen of the United States, residing at Roll, in the county of Roger Mills and State of Oklahoma, have invented certain new and useful Improvements in Telephone Attachments, of which the following is a specification.

My invention relates to improvements in telephone attachments and refers particularly to what may be termed a battery saver.

The main object of my invention is the provision of a telephone attachment for prolonging the life of the batteries, which while disconnected, will allow the bell to ring and which will not in the least impair the service on the line.

A further object of my invention is the provision of a telephone attachment for prolonging the life of the batteries, which will be simple, durable and practical and one which will be inexpensive of production.

With the above and other objects in view which will appear as the description proceeds, the invention consists in the novel construction, combination and arrangement of parts, hereinafter described and claimed, it being understood that changes in the precise embodiment of the invention, herein disclosed can be made without departing from the spirit of the invention.

In the accompanying drawings I have illustrated one complete example of the physical embodiment of my invention constructed according to the best mode I have so far devised for the practical application of the principles of my invention.

Figure 1 is a side elevation of a portion of a telephone box with my device attached thereto and shown in operative position.

Fig. 2 is a similar view with my invention in inoperative position.

Fig. 3 is a sectional view taken on line 3—3 of Fig. 1.

Fig. 4 is a sectional view taken on line 4—4 of Fig. 1, and

Fig. 5 is a sectional view taken on line 5—5 of Fig. 1.

Many devices and divers forms of constructions of varying degrees of effectiveness are now in use whereby the transmitter and the receiver of a telephone are disconnected from the batteries, thereby saving the batteries, the bell being free to ring at all times.

As will hereinafter appear, I provide by

my invention simple means for prolonging the life of telephone batteries, the said means being so constructed as to permit of ready repair and as will be obvious will not in any manner impair the telephone service.

In the drawings, the numeral 1 designates the side of the telephone box in which the batteries are usually placed and to which my invention is attached, although my device may be placed in any desired position where it will perform its functions in an efficient manner.

My device consists of the bar 2, pivoted to the box 1, by means of the screw 3, passing through the opening 4, in the bar, the bar having formed thereon the pair of switch or contact blades or tongues 5 and 6 adapted to engage the spring contact plates 7 and 8, respectively, and the handle or grasping portion 9.

The spring contact plates 7 and 8, have secured thereto by means of the screws 10 and 11, the wires 12 and 13, which lead to the battery and transmitter, respectively. The screws 10 and 11 also act as the fastening means for securing the plates 7 and 8 to the telephone box 1.

As will be readily seen by reference to Fig. 3 of the drawings, the contact blade 6 is set off from the bar 2 by means of the insulating material 14, to prevent a short circuit and has secured thereto by means of the binding nut 15, the wire 16, which leads to the battery, and by reference to Fig. 4 it will be seen that the blade 5 is integral with the bar 2.

The bar 2 is also provided with the ear 17, which carries the binding nut 18 which secures the wire 19, thereto, this wire leading to the receiver as will be readily understood by those skilled in the art to which this invention appertains.

Thus it will be apparent that when the device is in the position shown by Fig. 1, uninterrupted service may be obtained, and that when in the position shown by Fig. 2, the bell alone is connected with the batteries, thereby preventing the wastage or leakage of the electric currents, as is the case in the ordinary phone.

I claim:

1. In a switch for the purpose described, the combination with a suitable base, of a bar pivoted thereon having a pair of contact blades, one of said blades being integral with the bar and the other set off therefrom.

by means of insulating material, an ear integral with said bar, spring contact plates secured to the base and adapted to contact with the blades, and terminals on said ear plate and insulated blade for receiving suitable electric connection, substantially as described.

2. In a switch for the purpose described, the combination with a suitable base, of a bar pivoted thereon having a pair of oppositely disposed contact blades, one of said blades being set off from the bar by means of insulating material, a terminal carried by said insulated blade serving to secure said blade on the bar and adapted to receive a

suitable electric connection, an ear integral with the bar and having a terminal thereon to receive an electric connection, a handle formed on the end of the bar opposite said insulated blade, and contact plates secured to the base and having terminals for receiving electrical connections, said plates being so arranged as to contact with said blades substantially as described. 20

In testimony whereof I affix my signature 25
in the presence of two witnesses.

HUGH V. JOBE.
